SAFETY OVERALL

Leonard Gregory Johnson, San Rafael, Calif., assignor to Safe-T-All Corporation

Filed Feb. 9, 1972, Ser. No. 225,024

Term of patent 14 years

Int. Cl. D2—02

U.S. Cl. D2—29

FIG. 3

FIG. 1 is a front elevational view of a safety overall showing my new design;

FIG. 2 is a rear elevational view thereof; and

FIG. 3 is a side elevational view, the other side being a mirror image thereof.

I claim:

The ornamental design for a safety overall, as shown and described.
